UNITED STATES PATENT OFFICE.

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

CUTTING-MACHINE.

1,376,537.

Specification of Letters Patent.

Patented May 3, 1921.

Application filed December 19, 1917. Serial No. 207,869.

To all whom it may concern:

Be it known that I, JOHN B. HADAWAY, a citizen of the United States, residing at Swampscott, in the county of Essex and 5 State of Massachusetts, have invented certain Improvements in Cutting-Machines, of which the following description, in connection with the accompanying drawings, is a specification, like reference characters on the 10 drawings indicating like parts in the several figures.

This invention relates to cutting machines, and particularly to machines for cutting blanks from sheet material by means of a 15 die.

A cutting machine, which is extensively used at the present time, comprises a vertically reciprocating post or plunger arranged at one side of a stock supporting bed, a pressure member carried by the post and arranged to extend over the bed, and means for controlling the pressure member both as to its location and time of actuation, the 20 said means consisting of a spring supported handle which is grasped by the operative in 25 swinging the pressure member over the bed to the desired location and which is then depressed to act as a starting mechanism that initiates the operative stroke of the 30 pressure member.

It is an object of the present invention to improve the controlling means for the pressure member in the type of machine described by providing a construction in the 35 operation of which there is less possibility of premature actuation of the starting mechanism. In carrying out this idea there is provided a handle in a location accessible to the operative and, in juxtaposition to the 40 handle and operable independently thereof, a starting means for controlling the operation of the pressure member. As shown, the invention may be said to comprise, in a machine of the class described having a cutting bed and a pressure member with its 45 operating mechanism, the provision of means for controlling the pressure member comprising a handle on the pressure member and a starting means located in the handle and operable independently thereof in 50

such manner as to render unlikely the premature actuation of the machine.

In the type of machine described above, a hand-operated lever has been commonly used as the means for throwing the machine 55 into operation. In the illustrative machine, control of the power operating mechanism is obtained by means of a device in an electrical circuit comprising a switch or button mounted in a location accessible to the operative. There is a distinct advantage in 60 the press button or switch over prior mechanical arrangements inasmuch as the very minimum of effort is needed to make the necessary contact to close the circuit which 65 controls the starting mechanism. It is obvious, moreover, that the switch or button and its connections, because of size and compactness, may be readily located in positions most favorable for operation on the part of 70 the operative. From another aspect then, the invention may be said to comprise, in a machine having a cutting bed and a pressure member with its operating mechanism, the provision of a device in an electrical 75 circuit for controlling the operating mechanism and means, mounted in the handle that is grasped to move the pressure member, for opening and closing the circuit.

Other features of the invention will appear from the following detailed description with reference to the accompanying drawings, wherein a preferred embodiment of the invention is disclosed, and will be pointed out in the claims. 80

85 In the drawings:

Figure 1 is a view in side elevation of a cutting machine, parts being broken away to show the operating mechanism;

Fig. 2 is a sectional view of the oil switch 90 on the presser member;

Fig. 3 is a plan view from above of the oil switch with the cap removed; and

Fig. 4 is a plan view of the connection block with the covering removed. 95

For the purposes of illustration the invention is shown in a construction forming part of a cutting machine of a special type, known as the clicking machine. In this machine, the frame A is provided with bear- 100

ings B for a vertical post C having fixedly secured thereto the pressure member D. Inasmuch as the pressure member has a pressure surface of an area much less than that of the cutting bed E, it is necessary to mount the pressure member for oscillation over the cutting bed. Hence, the connections between the post C and the operating shaft F are such as to permit oscillation of the pressure member and post. These connections consist of a sleeve G threaded into the lower end of the post and carrying a shaft H rotatably mounted therein and connected at its lower end to an eccentric strap I surrounding the eccentric K on the operating shaft. In order to transmit motion to the shaft F a power pulley L is mounted loosely thereon and is arranged to be clutched to the shaft by clutch mechanism M partly housed in the flange N of the pulley. When it is desired to operate the clutch, the rod O is actuated to permit the clutching of the pulley to the shaft, the rod being operated in the well-known form of the machine by a lever or other mechanical means. Thus far the description applies equally well to the machine shown in Fig. 1 and to that disclosed in the patent to Bates, No. 921,503, granted May 11, 1909.

In the illustrative embodiment of the invention, the rod O is actuated by means of a device in an electrical circuit, the said device, in the present instance, being a solenoid housed in the casing 5 secured to the frame of the machine by a bracket 6. Pivotally secured to the upper end of the rod O, which has been lengthened over that shown in the patent, is a bar 7 located in the solenoid and arranged to be drawn therein when the circuit is closed, thus throwing in the clutch on the main shaft. The electrical circuit referred to comprises wires 8 leading from the source of electrical energy and attached to posts 9 and 10 in the connection block 11. Attached to the posts 10 and 12 are other wires 13 which lead through a tube 14 to form the solenoid in the casing 5. The circuit is nearly completed by another set of wires 15 attached to the posts 9 and 12 in the connection block and at their other ends to plates 16 in the member 17 located preferably on the pressure member D, the body of the wires being inclosed in an armored tube 18 extending between the connection block and said member. While any known form of push button or switch may be used, a handle for the pressure member being provided in close juxtaposition to said switch, it is preferred to make use of the ordinary commercial form of oil switch shown in detail in Fig. 2 of the drawings, inasmuch as the casing of the switch may be used as a handle in swinging the pressure member from and into position over the cutting bed. In the oil switch member the

plates 16 are connected by wires 19 to posts 20 secured in the insulation 21. In order to close the circuit a bridge 22 carried by the plunger 23 must be brought into contact with the upper ends of posts 20. This can be effected by slight pressure on the plunger, a spring 24 being provided for returning the plunger to its normally raised position. The cup or casing of the switch contains oil which covers the posts 20 as clearly indicated by the dotted lines in Fig. 2, the purpose being to prevent sparking upon making and breaking the circuit.

In the operation of the machine, sheet material is placed upon the cutting bed and a die is adjusted in any desired position upon the material. The operative then swings the pressure member D over the die, the casing for the oil switch or press button being used conveniently as a handle in effecting this operation. When the pressure member is above the die, the button or plunger 23 may easily be depressed by the pressure of a finger or thumb, to cause the clutch to be thrown into operation to permit a single revolution of the main shaft by which the pressure member is caused to descend upon the die and then to rise again to its normally elevated position. The pressure member may then be swung to one side to give a clear view of the work so that the die may be properly positioned upon the same.

The advantage of having a handle for the pressure member distinct from the press button or other starting means is found in the fact that when the two are combined it occasionally happens that the starting means is actuated prematurely, that is, before the pressure member is directly over the die. With the starting means in such close juxtaposition to the handle as in the present construction, it may be readily operated at the proper time by the same hand that swings the pressure member into place, with less likelihood of premature actuation of the starting means than in the construction with which comparison has been made above. A feature of importance in the specific form of starting means lies in the rapidity and ease with which it may be manipulated. When the die has been properly positioned and the pressure member swung into vertical alignment over the die, no appreciable mental or physical effort is required to start the machine into operation. It is obvious that this advantage is retained whether the special form of starting means be located on the pressure member or some other part of the machine. For reasons given above, however, it is considered most desirable to locate the starting means on the pressure member and in close juxtaposition to the handle.

Having described my invention, what I

claim as new and desire to secure by Letters Patent of the United States is:

1. In a clicking machine, a cutting bed, a pressure member mounted for oscillation from and into position over the bed, a handle fixed to the pressure member to be grasped in oscillating said member, power means for giving the pressure member reciprocatory movements toward and from the bed, a device in an electrical circuit for controlling the operation of the power means, and a switch mounted inside the handle on the oscillatable pressure member for opening and closing the circuit.
2. In a clicking machine, a cutting bed, a pressure member mounted for oscillation from and into position over the bed, a handle fixed to the pressure member to be grasped in oscillating said member, power means for giving the pressure member reciprocatory movements toward and from the bed, said power means comprising a shaft connected to the pressure member and a power pulley, a clutch operable to connect the shaft and the pulley, a device in an electrical circuit arranged to operate the clutch when the circuit is closed, and a switch mounted to project from the grip portion of the handle on the oscillatable pressure member and movable for opening and closing the circuit.
3. In a clicking machine, a cutting bed, a pressure member mounted for oscillation from and into position over the bed, a handle fixed to the pressure member to be grasped in oscillating said member, power means for giving the pressure member reciprocatory movements toward and from the bed, said means comprising a shaft connected to the pressure member and a power pulley, a clutch operable to connect the shaft and the pulley, a solenoid mounted on the frame of the machine and arranged to operate the clutch when the circuit is closed, and a switch comprising a plunger mounted inside the handle on the oscillatable pressure member and readily operable for opening and closing the circuit.
4. In a clicking machine, a cutting bed, a pressure member mounted for oscillation from and into position over the bed, power means for giving the pressure member reciprocatory movements toward and from the bed, a handle and a starting means both located on the pressure member in positions accessible to the operative, the starting means being movable in a direction substantially parallel with the axis of the handle and constructed and arranged for operation independently of the handle and by a slight downward pressure exerted by one finger of the hand which grasps the handle.
5. In a clicking machine, a cutting bed, a pressure member mounted for oscillation from and into position over the bed, power

means for giving the pressure member reciprocatory movements toward and from the bed, a handle fixedly attached to the pressure member in a location accessible to the operative, and a starting means located in the grip portion of the handle so that it may be operated by the same hand that grasps the handle and so constructed and arranged as not to be operable by the normal closing movement of the fingers of the hand in grasping the handle.

6. In a clicking machine, a cutting bed, a pressure member mounted for oscillation from and into position over the bed, power means for giving the pressure member reciprocatory movements toward and from the bed, a device in an electrical circuit for controlling the operation of the power means, a handle on the pressure member in a location accessible to the operative so that it may be grasped for causing oscillation of the pressure member, and means, mounted on the pressure member in close juxtaposition to the handle and movable in a direction substantially parallel with the axis of the handle, for opening and closing the circuit.

7. In a clicking machine, a cutting bed, a pressure member mounted for oscillation from and into position over the bed, power means for giving the pressure member reciprocatory movements toward and from the bed, a device in an electrical circuit for controlling the operation of the power means, a handle on the pressure member in a location accessible to the operative, and a switch, carried by the handle in such manner as to permit of closing movement of the fingers to grasp the handle without operating the switch and operable by the same hand that grasps the handle, for opening and closing the circuit.

8. In a machine for cutting sheet material by means of dies, a cutting bed, a pressure member mounted for oscillation from and into position over said bed, power means for giving the pressure member reciprocatory movements toward and from the bed to force the dies through the sheet material, a handle for causing oscillatory movements of the pressure member, and a starting means for initiating the operation of said power means constructed and arranged to be independent of the surfaces of the handle that are grasped to oscillate the pressure member and located inside the grip portion of the said handle and operable independently thereof.

9. In a machine for cutting sheet material by means of dies, a cutting bed, a pressure member mounted for oscillation from and into position over said bed, power means for giving the pressure member reciprocatory movements toward and from the bed to force the dies through the sheet material, a handle fixed to the pressure mem-

ber for causing oscillatory movements of the pressure member, and a starting means for initiating the operation of said power means, said starting means comprising a 5 press button in an electrical circuit, the press button being located in close juxtaposition to the handle and movable independ-

ently thereof in a direction substantially parallel with the axis of the handle by a finger of the hand which grasps the handle. 10

In testimony whereof I have signed my name to this specification.

JOHN B. HADAWAY.
